United States Patent

Des. 234,870
Patented Apr. 15, 1975

234,870

SPOT LIGHT

Arthur Schifrin, Atlantic Beach, N.Y., assignor to
Wallfrin La-Cal Industries, Inc., Brooklyn, N.Y.

Filed Jan. 31, 1974, Ser. No. 438,218

Term of patent 14 years

Int. Cl. D26—03, 02
U.S. Cl. D48—20 K

Fig. 1.

Fig. 5

FIG. 4.

FIG. 5.

FIG. 2.

FIG. 1 is a perspective view showing the top, front and right-hand side of a spot light according to my new design;

FIG. 2 is a front view thereof;

FIG. 3 is a side elevational view showing the left-hand side thereof;

FIG. 4 is a rear elevational view thereof; and,

FIG. 5 is a bottom plan view thereof.

I claim:

The ornamental design for a spot light, as shown.
